DISPENSING DEVICE

Frank W. Etter, North Attleboro, Mass.

Application December 27, 1935, Serial No. 56,392

5 Claims. (Cl. 221—62)

My invention relates to dispensing devices and more particularly to devices for dispensing tooth-powder for personal use.

One of the objects of the invention is the provision of a simple, inexpensive and practical device for quickly and efficiently placing a desired amount of tooth-powder on a tooth-brush with minimum waste of powder and with minimum muss accompanying this waste.

10 Another object is the provision of a powder dispensing device which is adapted to accommodate a fresh container of powder as one becomes exhausted all with minimum effort and inconvenience.

15 Another object of the invention is the provision of a dispensing device of the character described which readily lends itself to handling and packing for distribution and convenient mounting or positioning for use.

20 Other objects will be obvious in part and in part will be pointed out hereinafter.

In the accompanying drawing Figure 1 is a front elevation view of my dispensing device showing a tooth-brush in position to receive powder, and

25 Figure 2 is a side elevation of the device shown in Figure 1.

Like reference characters denote like parts in the several views of the drawing.

30 As conducive to a clearer understanding of certain features of my invention it may be noted at this point that at the present time substantially all of the dentifrices consumed by the buying public are in the form of various pastes. Of these there are a host on the market.

35 While the tooth-powders are known and widely recommended by the dental profession, their use is almost negligible in proportion to that of the various tooth-pastes. This general preference of a tooth-paste to a tooth-powder does not result from any superiority of the pastes in matters of taste, efficacy or economy but largely results from the relatively greater convenience attendant their use.

40 The successful application of tooth-powder to a brush requires a clear eye and a steady hand in addition to a certain amount of skill. Ordinarily in its use the powder is spilled about the room, falling from the brush or being ejected from an upset container. Muss and disorder usually accompany its use.

45 In general the pastes are easier to handle, easier to apply to a brush and considerably less mussy to use. Because of these practical aspects of use the pastes are preferred despite their

greater cost and lower efficiency as a cleansing agent.

Accordingly, one of the outstanding objects of my invention is the provision of a simple, inexpensive and thoroughly reliable device for dispensing tooth-powder for personal use in an efficient and direct manner requiring a minimum of skill and assuring a minimum loss of powder and a minimum muss attendant its use.

5 Referring now more particularly to the practice of my invention, attention is directed to the drawing wherein a tooth-powder container 10, illustratively in the form of a glass bottle having a threaded neck portion 10a and a sloping wall portion 10b, is mounted in an inverted vertical position with its neck portion extending downwardly. The container 10 is preferably maintained in the inverted position by sheet metal mounting means 11, illustratively secured to backing 12, conveniently secured to a wall 13 by means of a suitable fastening device generally indicated at 14.

10 The mounting means is secured to backing 12 in any suitable manner as by screws 15.

15 Sheet metal mounting means 11 is preferably fashioned of a bright corrosion resistant metal which is attractive to the eye, such as rustless iron or steel. The mounting means preferably includes arm portions 11a and 11b (see Figure 1) which extend outwardly from the backing 12 in a curved formation so as to securely embrace the cylindrical side-walls 10c of the container and maintain the container in a desired position. The lower portions of side-arms 11a and 11b, as seen in the drawing, are curved downwardly and inwardly, as generally indicated at 11c and 11d, to form a seat to accommodate the sloping walls 10b of the container.

20 A powder present in container 10 having an upper level, as indicated at 16, is released from the container by actuation of valve assembly 17 which conveniently threadedly engages the container neck 10a. The valve assembly preferably includes a measuring chamber, generally indicated at 17a, for accommodating a predetermined amount of powder and an actuating stem 17b which upon application of thumb pressure, for example, releases the predetermined quantity of powder from the container, the powder falling in a downwardly direction, as seen in the drawing, through a suitable outlet (not shown).

25 Powder released from container 10 by actuation of valve 17 falls upon a tooth-brush 18 maintained in a proper position beneath the outlet of valve 17. The proper positioning of brush 18 is

effected by a support and brush guide conveniently fashioned of a portion of the container support and generally indicated at 11e. This guide and supporting structure is U-shaped or 5 trough-like in construction and conveniently comprises a horizontal bed portion 11f projecting downwardly from backing 12 in a horizontal direction, as seen in Figure 2 of the drawing, with parallel upturned side-wall portions 11g 10 and 11h (see Figure 1). The guide and supporting structure assures the maintenance of brush 18 in a desired position beneath the outlet of valve 17. The brush need merely be placed in the brush guide and the valve actuated by a depression of 15 the stem provided. No skill is required in applying powder to the brush. Lateral movement of the brush is prevented by the side-wall portions of the guide. Where desired excessive longitudinal movement of the brush is prevented by a stop 20 conveniently formed by a bent end portion 11k of the support side-wall 11h.

By assuring accurate positioning of brush 18 immediately beneath the outlet of valve 17, it will 25 be seen that the powder released from the container falls entirely on the brush. As a result there is a minimum waste of powder and a minimum resultant disorder accompanying its use.

Thus it will be seen that there has been provided in this invention a tooth-powder dispensing device in which the various objects hereinbefore stated are achieved together with numerous accompanying practical advantages. It will be seen that the apparatus is simple, efficient, 30 pleasing to the eye and well calculated to assure efficient use of the inexpensive dentifrice tooth-powder. It will be seen that the device readily lends itself to the accommodation of fresh containers of powder with maximum ease and minimum effort in a simple direct manner.

40 While as illustrative of the practice of my invention a valve assembly is supplied independent of powder container, it will be understood that where desired the container may come equipped with a suitable valve. Likewise, if desired the 45 valve may be made integral with the mounting means.

Similarly, while the brush guide and support 50 are preferably fashioned as a portion of the member supporting the powder container, it will be understood that where desired an individual guide member may be employed. Furthermore, it will be understood that in the interest of economy in 55 production and simplicity in fabrication, the metal mounting comprising the support for the powder container and the brush guide may be used without benefit of a special backing member in which case the metal mounting is provided with suitable means for securing it to a wall for support.

60 As many possible embodiments may be made of my invention and as many changes may be made in the embodiment hereinbefore set forth it will be understood that all matter described herein,

or shown in the accompanying drawing, is to be interpreted as illustrative and not in a limiting sense.

I claim:

1. In a tooth-powder dispensing device of the 5 character described, in combination, a powder container having a neck portion, a sheet-metal wall mounting embracing and maintaining said container in an inverted vertical position, valve means engaging the neck portion of said container, and a sheet metal brush guide portion of 10 said wall mounting extending beneath the outlet of said valve and in approximate register therewith whereby powder in desired amounts is accurately released onto a brush positioned in said 15 guide.

2. In a tooth-powder dispensing device of the character described, in combination, a powder container having a neck portion, valve means 20 threadedly engaging the neck portion of said container, sheet metal means having arm portions embracing and maintaining said container in an inverted position for dispensing powder, and sheet metal brush guide means comprising an extension of said mounting means for positioning a tooth-brush immediately beneath the outlet of said valve means whereby powder in desired amounts is accurately released onto a brush positioned in said guide means.

25 3. In a tooth-powder dispensing device of the character described, in combination, a powder jar having a threaded neck portion, valve means 30 engaging said neck portion, sheet metal means having flexed spring-like arm portions embracing and maintaining said jar in a vertical position for dispensing powder in a downwardly direction in accordance with the actuation of said valve means, and brush guide means secured to said mounting for positioning a tooth-brush immediately beneath the said valve means whereby 35 powder in desired amount is dispensed onto a brush positioned in said guide means.

4. In a device of the character described, a sheet metal mounting comprising, in combination, a portion including spring-like arms for embracing and maintaining a powder container in an inverted vertical position, and a guide portion for positioning and maintaining a tooth brush immediately beneath a powder container positioned 45 in said first-mentioned portion.

5. In a device of the character described, a sheet metal mounting comprising in combination, a back portion securable to a wall, side-arm portions extending outwardly therefrom with inwardly extending lower edges adapted to embrace and support a powder container, and a U-shaped guide portion extending outwardly from the lower part of said back portion for positioning and maintaining a tooth brush immediately beneath a powder container mounted in the device.
